POUR SPOUT ATTACHMENT FOR A PAINT CAN OR THE LIKE

G. Dean Kenney and Joyce J. Kenney, both of 2437 Belknap Ave., Billings, Mont. 59101

Filed Mar. 19, 1971, Ser. No. 126,385

Term of patent 14 years

Int. Cl. D9—07

U.S. Cl. D9—290

FIG. 1.

FIG. 2.

FIG. 4.

FIG. 3.

FIG. 5.

FIG. 1 is a plan view of a pour spout attachment for a paint can or the like embodying our new design;

FIG. 2 is a front elevation view of the same;

FIG. 3 is a bottom view of the same;

FIG. 4 is a right side elevation view of the same, the left side being a mirror image of the same; and

FIG. 5 is a rear view of the same.

We claim:

The ornamental design for a pour spout attachment for a paint can or the like, as shown and described.
